UNITED STATES PATENT OFFICE.

CHARLES SCHOENFELD, OF CANTON, OHIO, ASSIGNOR TO THE DIEBOLD
SAFE AND LOCK COMPANY, OF SAME PLACE.

PRISON.

SPECIFICATION forming part of Letters Patent No. 424,936, dated April 1, 1890.

Application filed August 29, 1889. Serial No. 322,372. (No model.)

To all whom it may concern:

Be it known that I, CHARLES SCHOENFELD, a citizen of the United States, and a resident of Canton, county of Stark, State of Ohio, 5 have invented a new and useful Improvement in Prisons, of which the following is a full, clear, and exact description, reference being had to the accompanying drawings, making part of this specification.

10 My invention relates to improvements in prisons, the object of which is to provide a more secure prison, to simplify the construction, and to reduce the initial cost.

With these ends in view my invention consists of certain features of construction and combination of parts, as will be hereinafter described, and set forth in the claims.

Figure 1 is a view in perspective of a portion of a prison, illustrating my invention. 20 Fig. 2 is a view of an upper corner, also showing section on line xx , Fig. 1. Fig. 3 is a view in perspective of a perforated panel-plate. Fig. 4 is a vertical sectional view showing detail, full size. Fig. 5 is a horizontal sectional view showing detail of construction, full size. Fig. 6 is a vertical sectional view of modified form of construction, showing the body of the prison formed to receive the perforated plates and to which the plates are 25 directly secured; and Fig. 7 is a fragment of perforated panel-plate.

Similar letters of reference will indicate corresponding parts in all of the figures of the drawings.

30 Heretofore prisons of this class have been constructed of solid plates of metal and cross-bars of metal riveted together to form a lattice through which light and air is provided for the comfort and health of the occupants 40 of the prison, the overlapping bars referred to necessitating the use of an increased amount of material as well as labor in punching and riveting the bars together, both of which operations were not only expensive but 45 unsatisfactory, in this, that the strength of the bars was greatly reduced by the frequent perforations for the rivets by which they were secured together, and, finally, the structure was limited in strength to the 50 strength of the rivet. Thus after a magni-

tude of show a very unsatisfactory result was achieved, for by the use of an ordinary crow-bar placed in the apertures of the lattice that part of the structure could be torn apart and the object of the structure defeated.

55

The object of this invention is to provide a prison having all of the advantages of the structure hereinbefore referred to so far as related to providing light and air, and in addition thereto additional strength and security.

For the purpose of this application I have shown the body of the prison, including the floor and ceiling of the corridors, to be made of solid metal plates A B C. Said plates may 65 be wholly of iron or of steel, or the plates made of alternate layers of iron and steel welded together; but the essential feature of this invention consists in providing in a prison structure a wrought-metal perforated plate 70 D, as shown in Fig. 3, which plate is used in the construction of the cell, corridor, and doors, either in whole or in part, as well as in the panels E F, in the place of lattice-work formed by cross-bars in any of the usual and 75 well-known ways. The said plate D may be formed of any suitable metal, preferably iron or steel, or of alternate sheets of iron and steel welded together and rolled into sheets of desired thickness, forming a sheet of alternate layers of iron and steel. For the purpose of this case I have shown in the construction sheets of metal composed of layers of iron and steel, the two outside and the central layers a of iron, and the remaining two b of 80 steel.

In construction the plates for the panels E or doors F are provided of such size and form as may be required. The perforations d may be of any desired form or size, as their 90 only service is to admit air and light to the interior of the prison. The perforations may be made in any of the usual ways of punching by the use of a suitable die and punch operated by a press of such power as may be required. As the operation of punching is liable to slightly enlarge the plates, the sizing of them should be deferred until after that operation has been completed.

95 In the construction of doors metal stiles f 100

may be used to stiffen and strengthen the edge portion of the door. Said stiles or frames may be of any desired width, form, or ornamentation; but for the purposes of this application I have chosen a plain flat bar, the same as shown and used for the door-facings *h*, and in this case the same form of metal stile is used about the panels *F*.

To secure the plates *A*, *B*, *C*, and *D* in position to form a prison, as shown in Fig. 1, angle-irons, as *G* and *H*, are provided, between the flanges of which the ceiling and side portions *B*, *D*, and *A* are secured by rivets, as shown in Fig. 2, the flanges *j k* embracing the edge of the plate *B*, and the flanges *l m* embracing the plate *D*. Similar angle-irons *G* and *H* are also used to secure the floor portion *C* to the side panels *A* and *D*, the floor *C* being secured between the flanges *n o*, as shown in vertical section, Fig. 4; and similar angle-bars are used vertically at the corners *N*, by which the plates are secured in position.

In Fig. 6 is shown a vertical sectional view through the upper corner of a modification of construction, in which the top or ceiling plate *B* is bent at its outer edge portion, as shown at *s*, forming a right-angle flange portion *t*, overlapping the edge of the perforated plate *D*. The bottom plate *C* being formed in a similar way, the two portions will constitute a frame, against which the panel portions of the prison are secured.

As has been hereinbefore stated, the essential feature of this invention consists in providing a wrought-metal perforated panel-plate. I would therefore not be limited to any particular construction or form of frame.

Having thus fully described the nature and object of my invention, what I claim as new, and desire to secure by Letters Patent, is—

1. In a prison, the combination, with upper and lower plates, as *B* and *C*, forming ceiling and floor portions, of a wrought-metal plate

D, having perforations *d*, forming side panels *E*, substantially as described, and for the purpose set forth. 45

2. In prisons, the combination, with the upper and lower metal plates *B* and *C*, forming ceiling and floor portions, of the wrought-metal plates *D*, having perforations, as *d*, forming side and door panels, and an angle corner bar, by which said plates are secured together, for the purpose set forth. 50

3. In a prison, the combination, with the solid metal side, top, and bottom portions, as *A*, *B*, and *C*, of a side panel portion *E*, consisting of a wrought-metal plate having perforations, as *d*, punched or cut therein, through which air and light may pass into the prison, substantially as described. 55

4. In a prison composed in part of solid metal plates or other suitable material, wrought-metal plate *D*, having a solid marginal portion, and perforations *d*, whereby air 60 and light may be admitted into the prison, substantially as described.

5. In a prison, the combination, with a supporting-frame, of a wrought-metal side and panel having a solid marginal portion and 70 perforations cut or punched through its central portion, substantially as described, and for the purpose set forth.

6. A prison-door constructed of a wrought-metal plate having series of perforations, as 75 *d*, substantially as described, and for the purpose set forth.

7. In the construction of a prison, a metal plate composed of alternate layers of iron and steel, having series of perforations, substantially as described, and for the purpose set forth. 80

In testimony whereof I have hereunto set my hand this 1st day of August, A. D. 1889.
CHARLES SCHOENFELD.
